AUTOMATIC RAZOR

Emilian Bobkowicz, Westmount, Quebec, Canada

Application July 14, 1952, Serial No. 298,769

14 Claims. (Cl. 30—43)

1

The present invention relates to dry shaving razors and more particularly to the type of dry shaving razor which is manually actuated by contact with the skin surface to be shaved.

There are many and varied forms of dry shavers available which utilize a rotating or oscillating blade, or series of blades, in combination with a stationary perforated screen to achieve the desired shearing action. Many of these employ some form of drive, for example, electric motors, magnetic solenoids, or spring motors to give the cutting blades the desired shearing action. As will be appreciated, those driven by electricity require a power source, while the spring actuated type are necessarily of fairly complicated structure, and are therefore subject to mechanical failure over a period of use.

There are other forms of dry shaving devices which are driven by the manual engagement of some portion of the shaving mechanism with the skin surface to be shaved but in general these again are of fairly complicated structure.

The present invention aims to provide improved dry shaving razor constructions that are uncomplicated in structure and function, making their manufacture a more simple and less costly operation than the prior devices known.

Accordingly, the invention is a dry shaving device which includes a perforated screen portion adapted to be placed in contact with the surface to be shaved, face engaging traction members mounted for rotation about a central axis, and blade-supporting elements mounted for rotation beneath the screen. A plurality of cutting blades are mounted on each blade-supporting element in radially spaced apart relationship with their cutting edges disposed adjacent to the under side of the perforated screen surface and there are transmission means between the traction members and the blade-supporting element.

More specifically in one preferred construction of a dry shaving razor in accordance with the present invention the face engaging traction members consist of a pair of spaced apart circular discs which are mounted between outer and inner casing portions of the razor, so as to be free for rotation with respect to the perforated screen. Each traction member is shaped so as to be of circular form with the outer peripheral surface being toothed or serrated to provide maximum friction contact. Alternatively the outer peripheral surface of the traction member may be surfaced with a material giving it a more effective friction contact, for example, with rubber or the like. The axes, or shafts, on which the blade-

2

supporting elements are mounted are provided at each end with a fixed gear and a large gear is provided on each of the traction members which is in meshed engagement with the blade supporting element gears so that the traction members counter-rotate the blade supporting elements at a multiplied speed upon rotation by frictional engagement with the surface to be shaved.

The blade-supporting elements are mounted for rotation beneath the perforated screen so that they support the cutting blades in yielding contact with the under surface of the perforated screen. The cutting blades utilized may be of a variety of forms, all of which are substantially self-sharpening when embodied in the present razor construction.

In an alternative form of the present razor construction, a similar shaving mechanism is combined with a supporting casing and utilizes a single circular traction member centrally disposed between two sets of rotatable blade supporting elements. Similar driving and driven gears are provided on the traction member and blade supporting elements respectively so that rotation of the traction member through frictional contact with the surface to be shaved simultaneously counter rotates both sets of the blade supporting elements.

As before, the cutting blades utilized may be of a variety of forms, and may be made as integral parts of the blade supporting elements, or alternatively may be separate blade inserts fitting into suitable slots or recesses provided in the blade supporting elements.

Both of the preferred constructions are designed so that the razor construction is of a handy portable size particularly adapted for carrying in the pocket and each is designed so as to have the minimum of working parts. This application is a continuation in part of United States patent application Serial Number 284,566, filed April 26, 1952.

Having thus generally described the nature of the invention, particular reference will be made to the accompanying drawings illustrating by way of example preferred construction of dry shaving razors in accordance with the invention, and in which:

Figure 1 is a diagrammatic view in perspective elevation of one preferred construction of a friction drive razor in accordance with the invention, with the top cover shown as being removed.

Figure 2 is an enlarged sectional view in side elevation and in a trans-axial direction of the

construction shown in Figure 1 with the cover in closed position.

Figure 3 is a view partially in section of the top portion of the construction shown in Figure 1 to illustrate in more detail the arrangement of the driving traction members, the gearing and the blade supporting members.

Figure 4 is a side view in perspective of the removable top portion of the razor constituting the cutting mechanism.

Figure 5 is a sectional view along the diametrical centre line of the construction shown in Figure 1 with the cover in closed position.

Figures 6 through 9 are detail views in section of several alternative cutting blade arrangements suitable for use in the present razor construction.

Figure 10 is a top plan view showing an alternative razor construction embodying a single centrally disposed traction driving member.

Figure 11 is a sectional view of Figure 10 along the line 11-11 to illustrate the construction in more detail.

With particular reference to Figures 1 through 5 of the drawings one preferred construction of a dry shaving razor in accordance with the invention includes an outer casing having a main casing portion 10 serving as a handle when the razor is in use.

The casing 10 is made up of a pair of outer plates 10a, 10b which are mounted on a curved central joining plate 11. The plates 10a, 10b are provided with inwardly extending flanges 12 about the outer peripheral margins which fit into corresponding grooves 13 provided on the joining plate 11.

A pair of inner plates 16a, 16b are also mounted on the joining plate 11 in spaced apart relationship from each other and the plates 10a, 10b to form an inner compartment within the casing 10. The plates 16a, 16b include central openings 17 and a hollow cylindrical spacer 20 connects the plates 16a, 16b, so as to surround and seal off these openings.

The main driving mechanism of the razor is mounted on and between the plates 16a, 16b and the plates 10a, 10b as follows: A pair of circular traction driving members 30a, 30b are mounted, one at each side, between the plates 10a, 16a and 10b, 16b. Each traction member 30a, 30b is provided with an outer peripheral surface that is knurled or serrated as indicated at 32 and a large driving gear 34 which is concentrically disposed on the face of the member adjacent the plates 16a, 16b. An annular space 36 is provided between the traction portion of the members 30a, 30b and the gears 34 to provide a clearance for the application of the gears 34 in the drive to the cutting elements of the razor as will be described in more detail later.

The traction members 30a, 30b, also include concentric cylindrical extensions 37a, 37b having central openings 38 therethrough and which slidably fit through the openings 17 in the plates 16a, 16b to meet and interlock centrally forming a continuous spacer and connecting member for the traction members. In the construction shown the extension 37a is shaped so as to slidably fit within the extension 37b interconnecting the traction members for rotation with each other.

The casing plates 10a, 10b are provided with central openings 40 which are surrounded by inwardly extending bosses 40a, 40b which fit within the outer ends of the traction member

openings 38 so as to constitute bearing members about which the traction members are adapted to freely rotate.

The side plates 10a, 10b and the traction members 30a, 30b are retained in assembled condition by screws 33 passing through the openings 40 into threaded engagement with each end of a spacing sleeve bushing 52 fitting freely within the opening 38 provided in the traction member extensions.

The cutting mechanism of the razor is mounted as a unit in a removable assembly consisting of side plates 60a, 60b, connected at the ends by spacers 62. A perforated screen 64 is mounted on the side plates 60a, 60b and retained by screws 67 engaging the spacers 62. The screen 64 is shaped to provide a series of regularly spaced apart hemispherical corrugations and the side plates are correspondingly contoured along the upper edges. The side plates 60a, 60b are each provided with a plurality of radially spaced apart elongated openings 66. Blade supporting members 68a, 68b and 68c are mounted between the plates 60a, 60b, by shafts 70a, 70b, 70c, respectively extending through the openings 66. The ends of the shafts 70a, 70b, 70c extend beyond the plates 60a and 60b at each side and gears 80a, 80b and 80c are press fitted on these shaft ends.

The cutting head assembly is secured in operative position by means of screws 90 threadably engaged with the plates 16a, 16b at each side. The top portions of the inner plates 16a, 16b are recessed as indicated at 91 so that the lower edges of the plates 60a, 60b fit snugly in this recess. When assembled in this manner the driven gears 80a, 80b, 80c are accommodated in the clearance space 36 between the gears 34 and the outer surface of the traction members with the gears in meshed engagement with the gears 34 at each side.

Elongated springs 91a, 91b, are mounted on each side of the plates 60a, 60b and are shaped in an undulating contour so that a portion of the spring bears against the ends of each of the shafts 70a, 70b, 70c at each side resiliently urging, due to the elongation of the openings 66, the blade supporting member 68a, 68b, 68c upwards towards the inner surface of the perforated screen 64.

Each of the blade supporting members 68a, 68b, 68c, carries a plurality of cutting blades which may be integral extensions of the supporting member or alternatively, as shown, may be separate blade inserts mounted in radially spaced apart slots provided in the supporting members. These blades may be of the form shown in the preferred construction and indicated at 100, or alternatively may be of other forms or arrangements as shown in Figures 6 through 9.

With particular reference to Figure 6, a blade supporting member 103 is provided with seven straight edged blades 101 disposed in radially spaced apart relationship. The blades 101 are grooved adjacent the cutting edge at each side as indicated at 103 so that the blades will be sharpened as they are worn by their contact with the screen 64.

Figure 7 shows an alternative blade form 102 of a substantially T-shaped form so as to provide a double cutting edge to each blade with the blades mounted on a supporting member 68d in a similar arrangement as that shown in Figures 1 through 5.

Figure 8 shows a further alternative of blade form 104 as being mounted on a supporting member 105 so that the blades have the cutting edges disposed obliquely with respect to the perforated screen 64.

Figure 9 shows in more detail the cutting blade arrangement of the construction shown in Figure 11 wherein the blades 106 are disposed in spiral fashion presenting four elongated cutting edges. Preferably, in this form the blades 106 are integral extensions of the supporting member.

With particular reference to Figure 11 there is shown an alternative construction wherein a single traction drive member is mounted centrally of the casing and two sets of blade supporting members are mounted at each side of the traction member in radially spaced apart relationship in the manner of the preferred construction. In this construction the lower casing is made up of side plates 110a, 110b mounted to a curved joining plate 111 which also serves as a base and a support for spaced apart pairs of inner plates 116a, 116b and 119a, 119b. The plates, 116a, 116b, are each provided with a central opening 140 and bosses 142 which extend inwardly from each plate and surround the openings 140. The plates 116a, 116b, 119a, 119b each include a central opening 118.

The traction drive member 130 is provided with a knurled or serrated outer peripheral surface 150 to provide maximum friction contact and also includes annular recesses 151 at each side adjacent the outer periphery to provide a clearance space for the working of the driven gears and concentric extensions 172a, 172b extend from the member 130 at each side. The extensions 172a, 172b include a central opening 144 therethrough and slidably fit through the openings 118 of the plates 116a, 116b, 119a, 119b so that the bosses 142 of the plates 118a, 118b fit in the end of the opening 144 to serve as bearings for the rotation of the drive member 130. As in the earlier construction described, the casing side plates, traction member etc., are retained in position by screws 154 passing through the openings 140 and threadably engaging the ends of a spacing sleeve bushing 154 mounted within the opening 104 of the traction member extensions.

In this construction, blade supporting members, 160a, 160b, 160c and 170a, 170b, 170c are mounted on corresponding shafts 162a, 162b, 162c and 172a, 172b, 172c respectively between the opposing side plates 180a, 180b and 182a, 182b, of a pair of cutting heads similar to that shown in the first construction (Figure 4). As in the earlier construction, contoured perforated screens 190a, 190b are mounted on the side plates 180a, 180b. The ends of the shafts of the supporting members fit through and beyond elongated openings 129 arranged in radially spaced apart relationship in the side plates 180a, 180b and 182a, 182b and driven gears 200a, 200b are mounted on these shaft ends.

As is shown in Figure 9, the blades 106 in the supporting members are disposed obliquely or spirally relative to the axis of the members so that each blade presents a longer cutting edge to the respective perforated screen upon rotation. Contoured springs 104a, 104b, are disposed at each side of the cutting head assem-

blies and are mounted on the side plates 180a, 180b, 182a, 182b so as to act against the blade supporting shaft ends resiliently urging the members and the blades upwards towards the perforated screens.

The cutting heads or assemblies are secured to the inner casing plates by suitable screws engaging the plates 116a, 116b, 119a, 119b, the upper edges of these plates being provided with backing plates 212 for this purpose. When assembled in this manner the driven gears 200a, 200b are in meshed engagement with the driving gears 152a, 152b, so that rotation of the member 130 through frictional contact with the surface to be shaved causes a multiplied counter-rotation of the sets of blade supporting members producing the desired shaving action. As in the first described construction, a cover member 112 is provided to complete the casing.

In both razor constructions, there are provided openings 215a, 215b in the joining members 111 and 111 respectively which lead into the inner compartments to provide a means of discharging any cut hair dropping from the cutting blades to the interior of the devices.

I claim:

1. A manually operated dry shaving razor construction comprising a casing, a perforated screen fixedly mounted within said casing, at least one circular traction drive member mounted for rotation about a central axis within said casing and having an outer peripheral skin engaging surface extending beyond said perforated screen, a plurality of blade supporting elements mounted in radially spaced apart relationship for rotation within said casing beneath and adjacent to said perforated screen, a plurality of cutting blades mounted in equal spaced apart relationship on each of said blade supporting elements with the cutting edge of each blade adapted to contact the underside of said perforated screen in sequence, transmission means between said traction drive member and each of said blade supporting elements whereby rotation of said traction member through frictional contact with the skin surface to be shaved causes a multiplied counter-rotation of said blade supporting member.

2. A dry shaving razor construction as claimed in claim 1 wherein there are two circular traction drive members mounted in spaced apart relationship within said casing, one at each side of said perforated screen.

3. A manually operated dry shaving razor as claimed in claim 1 wherein the transmission means between said traction drive member and said blade supporting elements comprises, a driven gear connected to each of said blade supporting elements and a drive gear of greater diameter than said driven gears concentrically mounted on said traction drive member in meshed engagement with said driven gears.

4. A dry shaving razor as claimed in claim 1 wherein said casing is of circular form and is in two unequal parts with the upper part removable and said traction member, perforated screen, blade supporting elements and associated transmission means are mounted in said lower part.

5. A manually operated dry shaving razor construction comprising, a casing, a pair of perforated screens fixedly mounted within said casing in spaced apart parallel relationship, a circular traction drive member mounted for rotation about a central axis within said casing and between said screens and having an outer peripheral skin engaging surface extending beyond said screens, a

plurality of blade supporting members mounted in radially spaced apart relationship for rotation within said casing beneath and adjacent to each of said perforated screens, a plurality of cutting blades mounted in spaced apart relationship on each of said blade supporting elements with the cutting edge of each blade adapted to contact the underside of said perforated screens in sequence, transmission means between said traction drive member and each of said blade supporting elements whereby rotation of said traction member through frictional contact with the skin surface to be shaved causes a multiplied rotation of each of said blade supporting members.

6. A manually operated dry shaving razor as claimed in claim 5 wherein the transmission means between said traction drive member and said blade supporting elements comprises, a driven gear connected to each of said blade supporting elements and a drive gear of greater diameter than said driven gears concentrically mounted on said traction drive member in meshed engagement with said driven gears.

7. A manually operated dry shaving razor construction as claimed in claim 5 wherein there are two spaced apart opposed pairs of inner partitioning walls mounted within said casing and said traction drive member is mounted between said pairs of partitioning walls, said blade supporting members being each mounted in a shaft journaled between the opposing walls of one of said pairs of inner partitions.

8. A dry shaving razor as claimed in claim 5 wherein said casing is of circular form and is in two unequal parts with the upper part removable and said traction member, perforated screens, blade supporting elements and associated transmission means are mounted in said lower part.

9. A manually operated dry shaving razor construction comprising, a circular casing having a major lower portion and a minor removable upper portion, a perforated screen mounted in and extending radially above said lower casing portion, a pair of circular traction drive members mounted in spaced apart relationship for rotation within said casing, said traction members being disposed one at each side of said perforated screen with their outer peripheral surfaces extending beyond said screen, a plurality of blade supporting members mounted in radially spaced apart relationship within said casing for rotation adjacent to said perforated screen, a plurality of cutting blades mounted on each of said blade supporting elements in equal spaced apart relationship with the cutting edge of each blade adapted to contact the under surface of said perforated screen in sequence, and transmission means between said traction drive members and said blade supporting elements whereby rotation of the traction drive members through frictional contact with the skin surface to be shaved causes a multiplied counter-rotation of each of said blade supporting elements.

10. A manually operated dry shaving razor as claimed in claim 9 wherein the transmission means between said traction drive member and said blade supporting elements comprises, a driven

gear connected to each of said blade supporting elements and a drive gear of greater diameter than said driven gears concentrically mounted on each of said traction drive members in meshed engagement with said driven gears.

11. A manually operated dry shaving razor construction as claimed in claim 9 wherein there are a pair of inner partitioning walls mounted in spaced apart relationship within said casing and said drive traction members are mounted between said partitioning walls and casing, said blade supporting members each being mounted on a shaft journaled between said partitioning walls.

12. A manually operated dry shaving razor construction comprising, a circular casing having a major lower portion and a minor removable upper portion, a pair of perforated screens mounted in and extending radially above said lower casing portion, a circular traction drive member mounted for rotation within said casing lower portion, circular traction drive member mounted for rotation within said casing lower portion and between said perforated screens with the outer peripheral surface extending beyond said screens, a plurality of blade supporting members mounted in radially spaced apart relationship within said casing at each side of said traction member and beneath and adjacent to said perforated screens for rotation relative to said screens, a plurality of cutting blades mounted on each of said blade supporting elements in equally spaced apart relationship with the cutting edge of each blade adapted to contact the underside of one of said screens in sequence, transmission means between said traction drive members and said blade supporting elements whereby rotation of said traction drive members with the skin surface to be shaved causes a multiplied counter-rotation of said blade supporting elements.

13. A manually operated dry shaving razor as claimed in claim 12 wherein the transmission means between said traction drive member and said blade supporting elements comprises, a driven gear connected to each of said blade supporting elements and a drive gear of greater diameter than said driven gears concentrically mounted on said traction drive member in meshed engagement with said driven gears.

14. A manually operated dry shaving razor construction as claimed in claim 12 wherein there are two spaced apart opposed pairs of inner partitioning walls mounted within said casing and said traction drive member is mounted between said pairs of partitioning walls, said blade supporting members being each mounted in a shaft journaled between the opposing walls of one of said pairs of inner partitions.
